F. T. WENTWORTH.

LUGGAGE CARRIER.

APPLICATION FILED OCT. 28, 1916. RENEWED DEC. 8, 1919.

1,328,863.

Patented Jan. 27, 1920.

INVENTOR.

Frank T. Wentworth

UNITED STATES PATENT OFFICE.

FRANK T. WENTWORTH, OF BLOOMFIELD, NEW JERSEY.

LUGGAGE-CARRIER.

Specification of Letters Patent. Patented Jan. 27, 1920.

1,328,863.

Application filed October 28, 1916, Serial No. 128,148. Renewed December 8, 1919. Serial No. 343,424.

To all whom it may concern:

Be it known that I, FRANK T. WENTWORTH, a citizen of the United States, residing at Bloomfield, in the county of Essex and State of New Jersey, have invented certain new and useful Improvements in Luggage-Carriers, of which the following is a specification, reference being had therein to the accompanying drawings, which form a part thereof.

The invention relates to luggage carriers and more particularly to a type thereof adapted to be mounted upon the running board of an automobile in a manner to be capable of being quickly removed therefrom.

Luggage carriers of the type to which my invention relates are especially adapted for use in holding dress suit cases or similar articles of luggage and are generally used when an automobilist is touring; under which conditions there is ordinarily insufficient room in the tonneau of the vehicle to accommodate such articles. Carriers of this description, to have suitable capacity, must project beyond the edge of the running board, and under ordinary conditions it is not desirable to have such carriers permanently fixed to the running board. Luggage carriers made in accordance with my invention are so constructed that they may be readily and quickly secured to, and removed from, the running board, without mutilating said running board and without the use of tools. It is constructed of two independent parts, one of which is slidable in relation to the other, so as to permit the extension or contraction of the carrier to give it variable capacity to meet the requirements at any particular time. The two parts are provided with interlocking means which not only permit such adjustment, but, when the carrier is applied to the running board, prevent relative movement of these parts. The said interlocking means are held in the locked position by the clamp for attaching the carrier in its entirety to the running board.

The construction of the carrier is such as to space any luggage mounted thereon from the running board to an extent to protect the bottom thereof from water which may accumulate upon the running board.

Luggage carriers are used in pairs, each pair consisting of a set of irons so that the carriers may be so spaced apart upon the running board, as to accommodate them to

different lengths of bags or other articles of luggage.

The dimensions of a luggage carrier made in accordance with my invention are such that when it is not in use it may be readily stored under the seat of the vehicle.

A further advantage of a luggage carrier made in accordance with my invention is that both parts thereof may be made of cast malleable iron, require no machining beyond drilling and tapping for the clamp screw, and require no assembling operation beyond the insertion of the said clamp screw.

The construction of each set is such that it may have applied thereto a waterproof covering to protect the luggage or if desired it may be used with straps alone.

The invention consists primarily in a luggage carrier embodying therein a base having a loop at one end thereof and a bracket provided with an opening therethrough at the other end thereof, a clamp screw carried by said bracket and adapted to engage the under side of a running board and a slide having a loop on the outer end thereof adapted to pass through said opening in said brackets, said base having a plurality of grooves upon the under side thereof and said slide having a tongue upon the upper side thereof adapted to engage different grooves upon said base whereby the distance between said loops may be varied and the clamping action of said screw will hold said base and said slide in their adjusted position; and in such other novel features of construction and combination of parts as are hereinafter set forth and described and more particularly pointed out in the claims hereto appended.

Referring to the drawings:

Figure 1 is a perspective view of a portion of the tonneau of an automobile showing a luggage carrier made in accordance with my invention, applied thereto;

Fig. 2 is a detail view of one of the sets of irons showing ordinary straps applied thereto;

Fig. 3 is a section of a running board showing one of my luggage carriers applied thereto and the use of the waterproof cover in connection therewith; and

Fig. 4 is a diagrammatic view of the waterproof cover removed from the irons.

Like letters refer to like parts throughout the several views.

In the embodiment of my invention shown in the drawings, I have indicated at *a*, the running board of an automobile, upon which luggage carriers made in accordance with 5 my invention are adapted to be mounted. In the accompanying description, I will refer to the construction of a single set of irons, it being understood that said sets are used in pairs so spaced apart, as indicated in 10 Fig. 1 as to permit dress suit cases, or other articles of luggage, to be engaged adjacent the opposite ends thereof in a manner to firmly hold them against creeping longitudinally of the running board and swaying 15 laterally of the car.

Each set of irons comprises a base *b* having the inner end thereof upturned, as at *c*, and provided with a loop *c'* adapted to receive a strap or other securing means for 20 retaining articles of luggage upon the carriers.

The outer end of said base iron is provided with a bracket *d* having a set screw *e* adapted to engage the under side of the 25 running board *a*. To prevent loosening of the carrier through vibrations of the car or of the running board, I provide the screw *e* with a lock nut *e'*.

The head *f* of the bracket *d* is provided 30 with an opening *f'* extending therethrough below the plane of the bottom of the base *b* and passing through said opening is a slide *g*, the thickness of which is less than the depth of said opening *f'*. The outer end of 35 the slide *g* is provided with an upturned end *g'* having a loop *g''* adapted to receive a strap or other means for binding the article of luggage to the iron.

The under face of the iron *b* is provided 40 with a plurality of grooves *b'* and the upper face of the slide *g* is provided with one or more coöoperating tongues *g''*. Said tongues and grooves upon the base and the slide extend for the entire width thereof so as to 45 present coöoperating elongated bearing surfaces which will prevent movement of the outer end of the slide transversely of the running board.

By having the number of tongues *g''* less 50 in number than the grooves *b'* the slide *g* may be adjusted transversely of the base *b* so as to vary the width of the carrier and accommodate articles of luggage of different dimensions.

The under side of the base *b* adjacent the 55 upturned end *c* is provided with a downwardly projecting rest *h*, the depth of which corresponds, substantially with the thickness of the slide *g*, thus affording a support for 60 the base adjacent the inner end thereof when the slide *g* is extended to its full extent.

While the loops *c'-g''* may have straps 65 such as *i* permanently connected therewith as shown in Fig. 2, I prefer to use, with said irons, a waterproof covering which will

serve the two-fold purpose of protecting the articles of luggage carried by the iron and hold them firmly in position upon said carrier. This covering comprises a sheet *j* of suitable waterproof material provided with 70 top flaps *j'* adapted to project over the ends of the articles of luggage and side flaps *j''* each provided with suitable straps adapted to enter the loops *c'-g''* which straps are provided with buckles or other securing 75 means. Each of the side flaps *j''* is provided with oppositely disposed end flaps *j'''* which are adapted to fold over the top flaps *j'* and across the end of the articles of luggage. The end flaps *j'''* at each end of the cover 80 are provided with coöperating fasteners as shown in the drawing.

The operation of the herein described device is substantially as follows:

The slide *g* is passed through the opening 85 *f'* and the bracket *d* is passed over the edge of the running board of an automobile. The set screw *e* is then set against the under side of said running board to hold the iron in position and the luggage is placed upon 90 the irons. If it be found that the loops in the base and the slide of the irons are too widely, or not sufficiently widely separated, to receive the articles of luggage the slide *g* is adjusted longitudinally of the base *b*, the 95 set screw being released to permit the tongues *g''* to clear the tongues *b'*. When the slide *g* has been properly adjusted, the set screw is again set upon the running board drawing the base firmly against the 100 slide, the coöperating tongues and grooves upon said base and said slide firmly interlocking in a manner to cause the base to firmly clamp the slide in position. The lock nut *e'* may then be set sufficiently hard 105 to prevent vibrations loosening the screw. When the parts are so fixed upon a running board, they will be held firmly in position and will not become displaced by the ordinary vibrations due to the passage of the 110 vehicle even over rough roads. The elongated coöperating tongues and grooves will prevent any play of the slide.

This construction will also permit both the base and the slide to be made of cast 115 metal requiring no machine finishing and no assembling operation excepting that incidental to the mounting of the screw in the bracket.

If it is desired to cover the articles of 120 luggage it is merely necessary to form the covering about the luggage inserting the straps carried by said cover through the loops upon the base and upon the slide and draw the cover tight upon the said articles. 125 If it is not desired to use such a cover, the irons may be supplied with straps, one of which contains a buckle and the other of which is adapted to coöperate therewith. These straps are attached to the loops in 130

the base and the slide, and in securing the luggage in place are passed over the articles of luggage and drawn tightly thereon.

It has been demonstrated in actual use, 5 that irons made in accordance with my invention will hold articles of luggage such as suit cases firmly in place upon the running board; and that there is little or no likelihood of the irons becoming so loosened as 10 to permit their becoming displaced.

When the irons are not in use, they may be readily removed from the running board and stored about the automobile or in the garage.

15 It is not my intention to limit the invention to the precise details of construction shown in the accompanying drawings, it being apparent that the general design of the base of the slide may be varied without 20 parting from the spirit and scope of the invention.

Having described the invention what I claim as new and desire to have protected by Letters Patent is:—

25 1. A luggage carrier embodying therein a base having a loop at one end thereof, a bracket having an opening therethrough at the other end of said base, a clamp screw carried by said bracket and adapted to engage 30 the under side of a running board, a slide adapted to pass through said opening in said bracket and having a loop at the outer end thereof, said base having a plurality of 35 grooves upon the under side thereof and said slide having a tongue upon the upper side thereof adapted to enter different

grooves upon said base, whereby the distance between said loops may be varied and the clamping action of said screw will hold said base and said slide in their adjusted position, and means coöperating with the loop in said base and in said slide respectively for holding articles of luggage upon the carrier. 40

2. A luggage carrier embodying therein a 45 base having a loop at one end thereof, and a rest on the under side thereof adjacent said loop, a bracket having an opening therethrough at the other end of said base, a clamp screw carried by said bracket and 50 adapted to engage the under side of a running board, a slide adapted to pass through said opening in said bracket and having a loop at the outer end thereof, said base having a plurality of 55 grooves upon the under side thereof and said slide having a tongue upon the upper side thereof adapted to enter different grooves upon said base, whereby the distance between said loops may be varied and the clamping action of said screw 60 will hold said base and said slide in their adjusted position, and means coöperating with the loop in said base and in said slide respectively for holding articles of luggage 65 upon the carrier.

In witness whereof I hereunto affix my signature in the presence of two subscribing witnesses, this 18th day of October, 1916.

FRANK T. WENTWORTH.
